[57] CLAIM

The ornamental design for a paper tray for computer or similar article, as shown and described.

DESCRIPTION

FIG. 1 is a frontal perspective view of a paper tray for computer or similar article, showing my new design;
FIG. 2 is a left side elevational view, thereof, the side opposite being a mirror image;

FIG. 3 is a top plan view on a reduced scale;

FIG. 4 is a bottom plan view;

FIG. 5 is a front elevational view; and

FIG. 6 is a rear elevational view.

*FIG. 1**FIG. 2**FIG. 3**FIG. 4**FIG. 5**FIG. 6*
